Des. 1106

Anthony J. Gallagher & Jacob Bresley, of Philadelphia, Pa.
Assignors to

Anthony J. Gallagher, aforesaid,
Letters Patent, No. 1106, Dated June 7, 1859.

The schedule referred to in these Letters Patent and making part of the same.

To all whom it may concern:

Be it known, that we, Anthony John Gallagher and Jacob Bresley
both of the City of Philadelphia, and County of Philadelphia, and State of Pennsylvania,
have invented or produced a new and original design in Alto Relievo for a Corking Stove,
which we have named the "Beauty", and we do hereby declare that the following is a full
and exact description of the same. Reference being had to the accompanying drawing which
form a part of this Specification and in which

Fig. 1. Represents a front feeder door of the stove with its ornament, viz. -
raised dots, diamond shaped figures, a central oval figure, with corresponding oval figures

elongated, radiating from the central figure and increasing in size as they lengthen.

Fig. 2 A, Represents one of the front doors with its ornaments viz. Foliated ornaments, a central oval figure, with corresponding oval figures elongated, alternating with concave figures both radiating from the central figure and increasing in size as they lengthen being somewhat similar in character with those in Fig. 1.

Fig. 2 B, Part of the front plate of Stove with its ornament, viz. raised figures plain in form, placed one above the other forming a column.

Fig. 2 C, Part of the front plate of Stove same as B, with its ornaments viz. raised dots.

Fig. 3, Represents the oven door of the stove with its ornaments viz. Foliated ornaments or figures, a central oval figure, with corresponding oval figures elongated alternating with concave figures both radiating from the central figure and increasing in size as they lengthen being similar in character with those in Fig. 2, letter A.

All the ornaments or figures are in alto Reliev.

Fig. 4, Represents a section of the ornaments or figures on the side of the stove viz. a central oval figure, resting upon an ornament convex in form and tapering at the end.

What we claim and desire to secure by Letters Patent, is the arrangement, and combination of the ornaments that form the design hereinabove specified and represented in the accompanying drawings.

Witnesses,

3

Anthony John Gallagher.

Jacob Beesley.
